UNITED STATES PATENT OFFICE.

JOHN WUNDER, OF NEW YORK, N. Y.

DESIGN FOR A COLLAR BUTTON.

Application filed September 19, 1922. Serial No. 3,766. Term of patent 14 years.

To all whom it may concern:

Be it known that I, JOHN WUNDER, a citizen of the United States, residing at New York city, in the county and State of New York, have invented a new, original, and ornamental Design for a Collar Button, of which the following is a specification, reference being had to the accompanying drawing, forming part thereof.

Figure 3 is an elevation showing the design of the head and shank as seen from the side of the head.

I claim:

The ornamental design for a collar button, as shown.

JOHN WUNDER.
